CLAIM

The ornamental design for an electronic device display screen with a graphical user interface, as shown and described.

DESCRIPTION

The FIGURE is a front view of an electronic device display screen with a graphical user interface, showing the present design.

The broken lines showing an electronic device illustrate environmental subject matter, whereas the broken lines showing a display screen and elements of the graphical user interface illustrate portions of the article. None of the subject matter represented by the broken lines form part of the claimed design.
